AIR CONDITIONING APPARATUS

Humbert R. Rogant, Willoughby, Ohio

Application December 20, 1946, Serial No. 717,477

4 Claims. (Cl. 126—6)

1

My invention relates to air conditioning apparatus, more particularly to apparatus that may be used in combination with a heating source, or may be used separately, and the principal object of my invention is to provide new and improved air conditioning apparatus of the character described.

The invention has great utility for emergency or auxiliary heating, and thus has application any place where heat is required. For example, in warmer climates, a great many residences have no central heating system, and in those that have, the system is usually inadequate for relatively severe temperature drops. In many cases, in such warmer climates, although it is warm during the daytime, the evenings become uncomfortably cold, and heat is required to dispel the chill. The resident, if he has a central heating system, is compelled to start such system, or if without such system, must use presently available heating devices which have been found to be unsafe and inadequate.

Likewise, in the colder climates, especially during the spring and fall of the year, a resident hesitates to start the central heating system because of sharp fluctuations of temperatures. Also, in severe cold spells, the heating system may be inadequate, and may require supplementary heating means.

Quite frequently, housewives have lighted the kitchen stove to dispel the chill in the house, but this is far from satisfactory, since convection causes heat to rise, thus providing a condition wherein only a portion of the room is warm, and the remainder is cold.

My invention provides a heating device which may be readily and easily positioned on a stove or other heat source. Usually, although not restrictively, my heating device may be positioned on the top of a kitchen stove or range, and in this respect the invention has universal application, since practically every residence is provided with a cooking stove. Also, in this respect, my invention is particularly adaptable for use in apartments, where occupants of certain apartments desire more heat than the central heating plant provides. In this respect, great economy of fuel may be effected, since the central heating plant of an apartment building may be set to deliver a certain amount of heat which may be sufficient for ordinary usage, and persons, such as the sick, invalid or the like, may supplement this heat to their requirements by use of my invention.

Further, in practically all climates, particularly

2

during certain seasons, the evenings may be uncomfortably chilly, yet the days may be uncomfortably warm. My invention may be used in both cases, in combination with a heat source to dispel chill, and separately as a blower unit to move air in the manner of a fan.

In the drawings accompanying this application, and forming part of this specification, there is shown, for purposes of illustration, an embodiment which this invention may assume, and in these drawings:

Figure 1 is a perspective view of an embodiment of the invention as applied to the top of a cooking stove, a portion of the embodiment being broken away to better show its relation with the heating means of the stove,

Figure 2 is an enlarged vertical sectional view through the embodiment shown in Figure 1,

Figure 3 is a top plan view of the embodiment, a portion being broken away to show the interior, and

Figure 4 is a small scale side elevational view of the embodiment, showing a position it may assume when not in use, or when in use as a blower.

Referring to the drawings, the embodiment herein shown to disclose the invention comprises a housing 10 which may have a lower portion 11 of generally polyhedral formation, and an upper portion 12 in the general shape of a frustum of a pyramid. However, it will be understood that the housing may take any desired shape or form other than that herein shown.

The lower portion 11 has an opening 13 at its base, and is preferably formed with a beaded edge 14 for strength and safety purposes. The housing is adapted for position with a heating source, and in the embodiment herein shown, such source is a gas-type cooking stove 15.

The usual cooking stove has two or more heating means grouped together, and the housing 10 may cooperate with one or more of such heating means. As shown in Figure 1, the housing 10 covers four gas burners 16 (only two of which are shown), the burners being adapted to heat the interior of the housing.

As best seen in Figure 2, a grid 17, which may be of cast iron construction, is disposed inwardly of the opening 13, and divides the housing into a first compartment 18 entered through the opening and a second compartment 19 separated from the first compartment by the grid 17. The grid may have a series of pockets 20 formed therein to collect heat and to provide greater radiating surface. Preferably, the grid 17 has a plurality of

ears 21 which are secured to the walls of the housing 10, as by means of nut and bolt connections 22. It will be obvious, with the heating device as shown in Figure 1, that the heat from the heating means of the heat source will be directed against the grid 17.

The upper portion 12 of the housing 10 is formed with means providing for ingress and egress of air. In the embodiment shown, louvers 23 in the top and sides of the upper portion 12 provide for ingress of air, and louvers 24 in the sides of the upper portion 12 provide for egress of air.

The louvers 24 are preferably formed in less than all the sides of the upper portion, and in the case of a four-sided figure, two louvers 24 in adjoining sides, as shown in Figure 1, are preferred, so heat may be especially directed to any desired parts of the room by corresponding adjustment of the housing on the stove.

The louvers 24 are preferably of the air-dispersing type, and as best seen in Figure 2, each comprises a series of nested conical vanes held together and within the opening in the housing in any suitable manner, such as by cross ribs 25. As seen by the arrows in Figure 2, the louvers 24 disperse the heated air not only upwardly but also generally horizontally so as to generally reach all parts of the room.

Carried by the top of the upper portion 12 is an electric motor 26, and secured to the shaft of the motor, interiorly of the compartment 19, is a fan propeller 27. The motor 26 may be connected to any suitable source of electric current, and a switch 28, actuated by a thermostat 29, of standard construction, controls operation of the motor. The thermostat is preferably set so that the motor is energized only when sufficient heat is built up in the compartment 19, so as to prevent the blowing of unheated air into the room. The switch and thermostat are carried by a bracket 30 supported from a wall of the housing 10, tubing 31 protecting the wiring within the housing.

In operation, with the heating device, as shown in Figure 1, positioned so that the bead 14 rests on the top of a stove and circumscribes the burners 16, and with one or more of the burners in operation, heat rises into the compartment 18 and impinges against the grid 17. The grid is thus heated, and heats the air in the compartment 19 by radiation and conduction.

When the temperature in the compartment 19 reaches a desired amount, the thermostat 29 will close the switch 28 so as to cause energization of the motor 26. Air is drawn into the louvers 23 and is moved into engagement with the heated grid. The fan builds up a pressure in the compartment 19 so as to force the heated air outwardly of the louvers 24 and into the room with some velocity. If the temperature in the compartment 19 should drop below the desired amount, the thermostat 29 will open the switch 28 to deenergize the motor 26 until heat is again built up in the compartment 19.

Since the heating device will not be in use all the time, the housing 10 is provided with handle means and leg means to facilitate its transportation and its disposition on a surface other than as shown in Figure 1. In the embodiment herein shown, a handle 32 is formed of tubular stock, having its ends bent and formed with screw receiving lugs 33 which receive screws 34 passing through apertures in the housing 10. The feet in this instance are readily formed by

four balls 35 positioned on a side generally opposite to the side carrying the handle 32. The balls 35 are disposed in pairs, one pair at each end of the side, as seen in Figure 3. Each of the balls 35 is formed with a countersunk hole to pass a screw 36 which secures the respective ball to the housing.

The housing is attractively finished, and it may be supported upright on its feet 35 as shown in Figure 4, on the floor or any other supporting surface, either near the stove, or in any other suitable place.

In the event of a warm day or evening, the thermostat 29 may be adjusted so as to maintain the switch 28 constantly closed, and the device may be used as a cooling blower. In this event, the device is preferably supported by its feet 35, and may be conveniently moved to any position in the room.

From the foregoing, it will be appreciated by those skilled in the art that I have accomplished at least the principal object of my invention, and it also will be apparent to those skilled in the art that the embodiment herein disclosed may be variously changed and modified, without departing from the spirit of the invention, and that the invention is capable of uses and has advantages not herein specifically described; hence it will be appreciated that the herein disclosed embodiment is illustrative only, and that my invention is not limited thereto.

I claim:

1. A heating device, comprising: open-ended housing means adapted to have its open end rest on a stove surface in position so that heat from the burner means of said stove is directed into said opening; partition means spaced inwardly of said opening and extending transversely of said housing to divide said housing means into upper and lower compartments which are disposed on opposite sides of said partition means, the lower compartment being in free communication with said opening and thereby being adapted to receive heat from said burner means, said partition means having abutting engagement with said housing means to close communication between said upper and lower compartments so that objectionable fumes and products of combustion from said burner means are restricted against passage from the lower compartment to the upper compartment, said upper compartment having air inlet and outlet opening means; and air moving means for drawing air through said inlet opening means and exhausting it from said outlet opening means.

2. A heating device, comprising: open-ended housing means adapted to have its open end rest on a stove surface in position so that heat from the burner means of said stove is directed into said opening, partition means spaced inwardly of said opening and extending transversely of said housing means to divide said housing means into upper and lower compartments which are disposed on opposite sides of said partition means, the lower compartment being in free communication with said opening and thereby being adapted to receive heat from said burner means, said partition means having abutting engagement with said housing means to close communication between said upper and lower compartments so that objectionable fumes and products of combustion from said burner means are restricted against passage from the lower compartment to the upper compartment, said upper compartment having air inlet and outlet

opening means; and air moving means within said upper compartment for drawing air through said inlet opening means and directing it toward and into engagement with said partition means, the outlet opening means being positioned out of the movement of such incoming air so that air from said other compartment is exhausted therefrom by air pressure built up therein.

3. A heating device, comprising: open-ended housing means adapted to have its open end rest on a stove surface in position so that heat from the burner means of said stove is directed into said opening; grid means spaced inwardly of said opening and extending transversely of said housing means to divide said housing means into compartments which are disposed on opposite sides of said grid means, said grid means providing a recessed surface on each side thereof for efficient heat transference and for preventing smooth air flow thereacross, one of said compartments being in free communication with said opening and thereby being adapted to receive heat from said burner means, said grid means having engagement with said housing means to preclude free gaseous communication between said compartments so that objectionable fumes and products of combustion from said burner are restricted against free passage to the other of said compartments, said other compartment having air inlet and outlet opening means; and air moving means for drawing air through said inlet opening means and exhausting it from said outlet opening means.

4. A heating device, comprising: open-ended housing means adapted to have its open end rest on a stove surface in position so that heat from the burner means of said stove is directed into said opening; grid means spaced inwardly of said opening and extending transversely of said housing means to divide said housing means into 40 compartments which are disposed on opposite

sides of said grid means, said grid means providing a recessed surface on each side thereof for efficient heat transference and for preventing smooth air flow thereacross, one of said compartments being in free communication with said opening and thereby being adapted to receive heat from said burner means, said grid means having engagement with said housing means to preclude free gaseous communication between said compartments so that objectionable fumes and products of combustion are restricted against free passage to the other of said compartments, said other compartment having air inlet and outlet opening means; and air moving means for drawing air through said inlet opening means and directing it toward and into engagement with said partition means, the outlet opening means being positioned out of the movement of such incoming air so that air from said other compartment is exhausted therefrom by air pressure built up therein.
